His Attorney.

UNITED STATES PATENT OFFICE.

OTTO F. PERSSON, OF ERIE, PENNSYLVANIA, ASSIGNOR TO GENERAL ELECTRIC COMPANY, A CORPORATION OF NEW YORK.

COMBINED SCAVENGING-PUMP AND COMPRESSOR.

1,154,336.

Specification of Letters Patent. Patented Sept. 21, 1915.

Application filed December 26, 1913. Serial No. 808,649.

To all whom it may concern:

Be it known that I, OTTO F. PERSSON, a citizen of the United States, residing at Erie, county of Erie, State of Pennsylvania, have invented certain new and useful Improvements in Combined Scavenging-Pumps and Compressors, of which the following is a specification.

The present invention relates to combined 10 scavenging pumps and compressors for supplying air to the working cylinders of an internal combustion engine for scavenging purposes and for supplying high pressure air for injecting fuel into the combustion 15 chambers.

My invention has for its object to improve the construction of such apparatus by decreasing the overall height, decreasing the number of parts, and reducing the cost 20 of manufacture. The improvement is directed chiefly to the construction of the scavenging pump, but certain features of the compressor are also modified to attain the desired results.

25 In the drawing which illustrates one of the embodiments of my invention, is shown a combined scavenging pump and compressor in vertical section.

1 indicates the base of the engine and 30 mounted thereon is a receiver 2 containing a chamber 3 that receives air from the scavenging pump. From this chamber air is supplied to the working cylinder or cylinders for scavenging purposes and also to the first stage of a multi-cylinder compressor by a pipe 4 indicated by a broken and dotted line. At one side of the pump is a double acting reciprocating valve 5 that controls the admission of air to and its discharge from said pump. It is actuated by 35 a lever 6 that derives its motion from an eccentric 7 mounted on the main shaft 8 of the engine. Air enters the valve casing through a suitable screen 9. The valve casing 40 10 is supported by the base and has ports 11 and 12 at its ends which communicate with the pump cylinder.

45 Mounted on top of the receiver is a casing 13 which supports the low pressure cylinder 14 of the compressor, there being connecting ribs 15 between the two. The cylinder is provided with a head 16 in which there are one or more inlet valves 17 and one or more discharge valves 18. The head 50 also supports the cylinder 19 of the high

pressure stage of the compressor. This latter cylinder is also provided with a head 20 containing an inlet valve 21 which receives its air from the valve 18 through the pipe 22, indicated by a broken and dotted line. 60 A discharge valve 23 is also provided in the head and high pressure or blast air is conveyed therefrom by the pipe 24, indicated by a broken and dotted line. Surrounding the compressor and mounted on the casing 65 13 is a cover 25 forming a cooling water jacket.

The pistons 26, 27 and 28 for the scavenging pump and high and low pressure stages of the compressor are formed in a single 70 unit. The stages of the compressor are single acting while the pump is double acting. The pump piston is of relatively large 75 diameter and comprises a peripheral portion containing packing rings that is connected to the trunk of piston 27 by an inclined web 29, said web forming the head of the piston. The lower part of the cylinder 14 also terminates in an inclined web 30 which in addition to supporting said cylinder forms the lower wall of the chamber 31 for the cooling water and also the upper 80 head of the pump cylinder. Inside of the receiver is a liner 32 forming the cylinder for the pump. It is provided with ports on one side that register with ports 11 and 12 in the valve casing 10. The lower wall of the receiver extends horizontally and mounted thereon is a tubular member which has an inclined web 33 forming the lower 85 head for the pump cylinder and a cylindrical part 34 forming an inverted guide for the piston 26 and also one wall of the pump cylinder, the two parts being in telescopic relation. It will be seen that the pump cylinder comprises a part of relatively large 90 diameter and a part of smaller diameter between which the piston moves.

The object of inclining the web or head 95 33 of the pump cylinder is to provide sufficient space for the connecting rod without however unduly increasing the diameter of the cylinder. Since the part 33 is inclined, it follows that the pump piston and the upper cylinder head must be similarly inclined 100 if small clearances are desired at the ends of the piston strokes, as in the present instance.

In order to guide the piston and prevent 105 air from passing from the cylinder space 110

through said tubular member, the inside of the hollow compressor piston 27 is turned to form a true cylinder and projecting into it is the upper end of said member, there being suitable packing rings 35 between the two. By preference these rings are mounted in grooves formed in said member. In order to provide the necessary strength the member may be provided with longitudinally extending ribs 36.

By inverting the tubular member instead of letting it project below the level of the receiver and cylinder head 33 it is evident that considerable space in a vertical direction is saved because the cylinders when considered together can be brought nearer to the main shaft. Sufficient space is also provided for the connecting rod 37 to swing back and forth as it is moved by the crank 20 38. Forming the pistons 26 and 27 in a single unit results in a saving in the number of parts and also simplifies and reduces the cost of the machine work.

I regard it as being desirable to make all 25 three pistons in a single unit but this is not necessary. It will, however, be found preferable to make the pump and low pressure pistons as a single unit to reduce weight and cost of machining, and also to avoid special 30 and irregular shapes and extra parts.

Arranging the tubular member in telescopic relation with the piston 27, besides decreasing the height of the apparatus as a whole, affords a simple means for forming 35 the inner wall of the pump cylinder and also permits the use of a relatively long connecting rod, and one which can be connected to the low pressure piston of the compressor, as is desirable, to obtain the most satisfactory 40 operation. In addition to the features above specified the construction is advantageous because the parts may be readily taken down and reassembled when necessary.

In accordance with the provisions of the 45 patent statutes, I have described the principle of operation of my invention together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

55 1. In an apparatus of the character described, the combination with a pair of pistons comprising a tubular member which forms one of them, an inclined web member surrounding it and having a peripheral portion which forms the other, a cylinder for

the tubular piston member and a cylinder for the other, said last named cylinder comprising a stationary member in telescopic relation with the tubular piston member, a second stationary member surrounding it, and means associated with the stationary members forming heads for the cylinder.

2. In an apparatus of the character described, the combination of a trunk piston, a second piston carried by the trunk of the first, a stationary tubular member which projects into said trunk and forms a head and inner cylinder for the second piston, an outer cylinder for the second piston, a cylinder for the trunk piston, valve means for the cylinders, and a driving means for the pistons.

3. In an apparatus of the character described, the combination of a trunk piston, a second piston which comprises a peripheral portion and an inclined web that connects it to the trunk of the first, an outer cylinder for the second piston, a member comprising a tubular portion that is in telescopic relation with said trunk and forms a part of a cylinder for the second piston and has an inclined web which supports said portion and forms a cylinder head, a cylinder for the trunk piston, an inclined web for supporting it that also forms a head for the second cylinder, valve means for the cylinders, and driving means for the pistons.

4. In a combination, a cylinder, a piston movable therein which has a central opening, a tubular member which makes a sliding fit with the wall of said opening and forms one wall of a cylinder for the piston, a connecting rod for driving the piston that extends through the member, a shaft connected to the rod, and valve means for the cylinder.

5. In a combination, a base, a receiver mounted thereon, a cylinder located in the receiver, a trunk piston, a web attached to the trunk and forming a second piston, a hollow member supported by the receiver which is in telescopic relation with said trunk and has a web forming a cylinder head, a cylinder for the trunk piston which is supported by the receiver and has a web that forms one head for the first named cylinder, valve means for the cylinders, and a driving means for the pistons.

In witness whereof, I have hereunto set my hand this 19th day of December 1913.

OTTO F. PERSSON.
